UNITED STATES PATENT OFFICE.

PARKER WELLS, OF LYNN, MASSACHUSETTS.

FILTER.

SPECIFICATION forming part of Letters Patent No. 244,701, dated July 19, 1881.

Application filed May 18, 1881. (Model.)

To all whom it may concern:

Be it known that I, PARKER WELLS, a citizen of the United States, residing at Lynn, in the State of Massachusetts, have invented certain new and useful Improvements in Filters; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to a device adapted for filtering water, or the like, to be placed upon the exit end of a water-pipe, or in other desired location; and the novelty consists in the construction and arrangement of parts, as will be more fully hereinafter set forth, and specifically pointed out in the claims.

The object of the invention is to furnish a cheap, simple, efficient, and portable filter, which will allow the water to be reversed through the filtering-chamber at will when filtering the water or cleansing the material is desired, and also allow the water to pass directly through the body of the filter in an unfiltered state, when desired, as will be explained.

The invention consists, essentially, in a body the external contour of which approximates an ogee curve, said body being of any suitable metal, and preferably nickel-plated, as shown. Cast in one piece therewith is a diametrical cylindrical chamber, between which and the body is formed a chamber which extends from one side to the other, said chamber being adapted to contain the filtering material, which is preferably charcoal, but other material may be used if desired.

The cylindrical chamber mentioned connects with the filtering-chamber by a proper aperture upon each side, and said chambers are separated by a gauze or other finely-meshed screen, which serves to hold the filtering material in place. These side apertures are governed by a three-way valve having a central plate, which will extend from the lower edge of one aperture to the upper edge of the other, a circular head having a cut-away portion in which is received a pin secured to the body, which limits the action of the valve, a circular head upon the other extremity to close the

chamber at that point, a threaded nut which screws into the body, a shank extending through said nut, and a convenient operating means upon the outside.

To the upper edge of the body, by thread-connections, is secured a cap, which has a seat upon the horizontal surface of the body and rectangular frame, and which is provided with a threaded connection to the house-supply pipe or faucet.

To economize metal the rectangular portion of the casting is cut away; and to prevent the water from rising at these points a disk of leather, rubber, or other suitable material having a central perforation, is placed between the screw-cap and the body, said disk serving the double function of making the valve-chamber water-tight at these points, and also serving as a packing for the screw-cap. From the valve-chamber an aperture leads downward through the neck to form an exit for the water. This neck may be provided with screw-threads or other connections for attachment for further pipes.

In the accompanying drawings, Figure 1 is a central vertical section; Fig. 2, a section at right angles thereto; Fig. 3, a top-plan view, with cover and plate removed; and Fig. 4, a detail view of the valve.

Referring to the drawings, A represents the body, of compound-ogee contour, having exit-neck b, and an outwardly-extending portion, b', carrying a female-threaded flange, b², which receives a cap, C, threaded at c, and having central-threaded pipe-connection, c'.

Cast in one piece with the body A is a frame, B, which is rectangular for a portion of its extent, and which forms between itself and the body a filtering-chamber, D, as shown. In this frame is formed a cylindrical chamber, H, having side openings, h, and a gauze or other screen, x, at each aperture, to separate the valve-chamber H from the filtering-chamber D. The upper portion of the frame B has a central opening, b³, which corresponds with the opening in the pipe-connection c', and allows the water to pass directly from the supply-pipe into the valve-chamber, and upon each side of the central aperture are cut-away places b⁴, which economizes metal and enlarges the chamber. A packing-disk, I, having a central aperture, i, is placed between the cap and the frame to close

the openings b^4 , and to operate as a packing for the cap C.

b^5 represents an opening from the valve-chamber downward through the exit-neck b.

5 K represents a three-way valve, having a central plate, k, a head, k' , upon the inner end, cut away at k^2 , a head, k^3 , upon the other extremity, a shank, k^4 , and an outer operating means, k^5 .

10 Operating in an aperture, b^6 , by threaded connection, is a screw-nut, m, which partially incloses the head k^3 and operates loosely upon the shank k^4 , or allows the shank to operate loosely therein. The cut-away portion k^2 receives a pin, x' , which limits the oscillations of the valve, as shown.

The operation of the device is as follows: The water entering the valve-chamber is deflected through one of the side openings, h, 20 through the filtering material, below and around to the opposite side, through the other opening h, beneath the valve, and out through the neck b. When the filtering material becomes dirty or clogged it is readily cleansed by 25 changing the valve to its extreme limit in an opposite direction, which action thoroughly cleanses the material, the water thus used being allowed to go to waste, if desired. When the valve is turned one-half its stroke the water is allowed to pass freely through the device 30 in an unfiltered condition.

I attach importance to the frame, the screw-cap, and the packing-disk.

I attach importance to the three-way valve,

having cut-away portion, and the pin for limiting the valve action. 35

What I claim as new is—

1. A filter having a body, an exit-neck, and a contained rectangular frame of the form described, cast in one piece to form a filtering-chamber, and a valve-chamber having side apertures connecting therewith, and being provided with a removable top having connections for attachment to the source of supply, adapted to serve with a three-way valve, as specified. 40

2. The body A, neck b, threaded flange b^2 , and rectangular frame B, cast in one piece, as shown, combined with the perforated disk I and cap C, as and for the purposes set forth. 45

3. The combination of the body A b^1 b^2 and frame B, cast in one piece to form filtering-chamber D and valve-chamber H h , the screens x, disk I i, cap C c' , and a three-way valve, as and for the purposes set forth. 50

4. The valve K, composed of the central plate, k, heads k' k^3 , shank k^4 , and handle k^5 , combined with the nut m and casting A B b, having threaded apertures b^6 , as set forth. 55

5. The valve K, having head k' cut away to form a segmental space, k^2 , combined with the body having pin x' , to limit the stroke of the valve, as specified. 60

In testimony whereof I affix my signature in presence of two witnesses.

PARKER WELLS.
